UNITED STATES PATENT OFFICE.

BURNHAM C. STICKNEY, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,270,241.

Specification of Letters Patent. Patented June 18, 1918.

Application filed October 13, 1911. Serial No. 654,535.

To all whom it may concern:

Be it known that I, BURNHAM C. STICKNEY, a citizen of the United States, residing in Elizabeth, in the county of Union and 5 State of New Jersey, have invented certain new and useful Improvements in Combined Type-Writing and Computing Machines, of which the following is a specification.

This invention relates to combined type-writing and computing machines of the kind 10 in which a relative step-by-step movement is effected between the master wheel and a system of computing wheels concomitantly with the letter-feeding movements of the 15 carriage of the typewriting machine, and in which a rotation or movement of the master wheel or device is effected as each key is operated.

The object of the present invention is to 20 provide improved means for preventing an improper or incorrect action of the computing wheels due to the liability of the master wheel being rotated while the typewriter carriage is in motion, or before it has left 25 one computing wheel and been brought into proper engagement with the next. By means of this device, the necessity is avoided of providing or relying wholly upon stop devices for preventing simultaneous rotation 30 of the master wheel and traveling movement of the carriage.

The improvements are illustrated in connection with a computing head which is connected up to the paper carriage to travel 35 therewith, while the master wheel does not travel with the paper carriage; but it will be understood that the invention is applicable to machines in which the master wheel travels step-by-step while the computing 40 head does not travel with the paper carriage; or in which both master wheel and computing wheels travel simultaneously, but in opposite directions.

According to this invention, the master 45 wheel is rotated by the finger key during the early part of the key stroke; and after such rotation and before or during the completion of the key stroke, the master wheel jumps to the next computing wheel in the 50 system, that is, to the wheel of next lower denomination, instead of remaining in mesh with the computing wheel which it has just rotated. This jumping of the master wheel is effected automatically and anticipatively, 55 or in advance of the ensuing letter-feeding

movement of the carriage, which usually occurs during the return stroke of the numeral key.

Heretofore, in key driven computing mechanisms, it has been the custom for the 60 master wheel to remain in mesh with the dead computing wheel, that is, the computing wheel which it has just rotated, until after the key had returned to normal position, and until after the carriage had completed its ensuing letter spacing movement; and hence the master wheel has remained uselessly in engagement with the dead computing wheel for a comparatively long time. According to the present invention, the 65 master wheel immediately leaves the dead computing wheel and jumps to the live computing wheel in advance of the movement of the carriage, so that if a succeeding key is depressed before the carriage movement is 70 completed, it will cause the master wheel to rotate together with the computing wheel, even though said wheels are traveling with the carriage. Hence faulty operation cannot occur, and the necessity of using complicated interlocking mechanisms is avoided. The master wheel is very light and moves 75 quickly so that it can jump the short distance required before there is any liability of an operation of a succeeding key, and 80 in fact this jumping movement of the master wheel may be completed by the time the first key has finished its down stroke, so there is no liability of clashing of any parts 85 of the mechanism. The master wheel is 90 normally in mesh with the live computing wheel, and, after turning the latter, the master wheel immediately jumps to the next computing wheel, where it remains until the next key has operated, so that there is hardly 95 any interval of time during which the master wheel is in mesh with the dead computing wheel. This saving of time is important not only because it permits speed of operation, but also because it renders it unnecessary to hamper the operator by a system of locks.

I arrange to disconnect the numeral key from the master wheel during the down stroke of the numeral key, preparatory to 105 the jumping movement of the master wheel; and at the last part of the down stroke of the numeral key a spring is caused to advance the master wheel to the next computing wheel; this movement being controlled 110

by the numeral key, which, after effecting this purpose, is disconnected from the master wheel; so that the computing devices are operated and the master wheel is repositioned, and all these parts disconnected from the numeral key by the time it has completed its printing stroke, thus insuring quickness of operation of the automatic mechanism and clearing a way for the operation of the 10 succeeding key before the first key has entirely returned to normal position, and before the paper carriage has made its ensuing letter feeding movement. The master wheel can perform its function of turning 15 the computing wheel both when the carriage is stationary and also when the carriage is moving, so that there is a relatively long interval of time during which rotation of the master wheel can perform its function, 20 instead of the extremely limited time as heretofore.

The feature of disconnecting the key from the master wheel during the down stroke of the key has further advantages, which 25 may also be employed in machines in which there is no relative anticipative jumping movement between the master wheel and the computing wheels.

Upon the return of the key to normal position, it reconnects automatically with the computing mechanism for effecting a subsequent operation of the latter.

Other objects and advantages will hereinafter appear.

35 In the accompanying drawings,

Figure 1 is a sectional view similar to a part of Fig. 3, showing particularly the normal position of an overthrow check for the master wheel.

40 Fig. 2 is a perspective view of a spiral series of key-operated arms projecting from a rock shaft which drives the master wheel.

Fig. 3 is a sectional side elevation taken longitudinally through an Underwood front 45 strike typewriting machine, showing the present improvements applied thereto.

Fig. 4 is a front elevation of the machine, showing the parts in normal positions.

50 Fig. 5 is a plan of the numeral keys of the typewriter.

Fig. 6 is a plan of the connection between the computing mechanism and the typewriter carriage escapement wheel.

55 Fig. 7 is a rear elevation of a wheel driven by the typewriter carriage and a pawl mechanism associated therewith to vibrate the master wheel 29 seen at Figs. 1 and 3.

Fig. 8 is a view similar to Fig. 7, but showing the master wheel vibrating pawl as 60 silenced.

Fig. 9 is a sectional side elevation, showing the automatic disconnection of a numeral key from the master wheel driver.

Fig. 10 is a similar view, showing the key 65 wholly disconnected from the computing

mechanism prior to the completion of the printing or down stroke of the key.

Fig. 11 shows the key temporarily at the end of its down stroke, while the computing devices have returned to normal positions. 70

Fig. 12 shows the key returning to normal position.

Figs. 13 to 16 are views similar to Fig. 8, but showing different positions of the parts.

Fig. 13 shows the pawl 52 as just released 75 from the carriage driven wheel 54.

Fig. 14 shows the pawl 52 as intercepted by the pin 71 in case the releasing arm 51 should remain an undue length of time in its depressed position; whereby the spring 80 57 is enabled to cam the pawl 52 upwardly into engagement with the succeeding tooth of wheel 54.

Fig. 15 shows the pawl 52 in engagement with the succeeding tooth of wheel 54, to 85 enable the carriage to drive the master wheel, to cause the latter to accompany the carriage in its ensuing letter-feeding movement.

Fig. 16 illustrates what happens when an 90 alphabet key is employed for printing a type and feeding the carriage; the wheel 54 driving the pawl idly toward the left until cam 80 on the pawl is intercepted by fixed pin 81, thereby causing the pawl to escape 95 from the wheel, and permit it to jump into the next notch thereof under the tension of spring 57.

Fig. 17 is a front elevation, illustrating 100 the pawl 52 and master wheel 29 as silenced by the finger key 82; the dotted lines showing the normal position of the master wheel.

Fig. 18 is a view similar to Fig. 17, showing the parts in the same position as at Fig. 16. 105

Alphabet keys 1 and numeral keys 2 are mounted on levers 3 fulcrumed at 4 and connected by bell cranks 5 to type bars 6, which strike upwardly and rearwardly against a platen 7 as usual in the Underwood typewriting machine; said platen mounted on a carriage 8, which is propelled by a spring barrel 9 and has a rack 10 meshing with a pinion 11, to which is connected an escapement wheel 12 which is controlled by detent 115 and feeding dogs 13, 14. Each type bar has a heel 15 to press rearwardly a universal bar 16, the latter mounted on a frame 17 supported on its rear end by idle links 18 and operating the dogs 13 and 14 in the well 120 known manner, to cause the carriage 7 to feed at each type stroke.

Each of the numeral keys 2, bearing the numbers from "1" to "9," is provided with a connection 19, pivoted at 20 to the key 125 lever 3 and having at its upper end a hook or nose 21 to catch over one of a series of pins or lugs 22 formed upon the arms 23; the latter all fixed upon a rock shaft 24 of the computing mechanism, and projecting 130

rearwardly from said rock shaft. Said shaft also carries an arm 25 upon which is pivoted a driving pawl 26 to mesh with a ratchet wheel 27, which is fixed to a shaft 28 5 on which is carried a master wheel 29.

To the paper carriage 8 is connected a series of computing wheels 30 meshing with pinions 31 carried upon dial wheels 32; the computing wheels and dial wheels (together 10 with the usual tens carrying mechanism, not shown) being placed in a casing 33 supported upon arms 34 projecting forwardly from the carriage 8.

The arms 23 have a spiral arrangement; 15 the strokes of the connections 19 being uniform, and the arms 23 being placed so that different movements will be given by different keys to the master wheel 29, according to the value of the key. The parts 23 to 27 20 operate as an indexing mechanism to drive and determine the extent of rotation of the master wheel or member 29. Any other suitable system of computing wheels and master wheel and means for driving the master 25 wheel may be employed; as the parts 22 to 34 are used merely to illustrate one kind of computing mechanism to which the improvements can be applied.

Each connection 19 is in the form of a 30 trip which releases the pin 22 during the down stroke of the numeral key 2. This release may be effected in various ways, as by means of a trip bar 35 in the path of a cam or tappet 36 on the trip. When the type 35 bar has nearly reached the platen, as illustrated at Fig. 9, the cam 36, by coöperation with the trip bar 35, disengages the nose 21 of the trip from the pin 22; and a spring 37, connected to an arm 38 on the rock shaft 24, 40 returns the latter to normal position in advance of the return of the key 2 to normal position; said spring holding said arm 38 up against a stop 39. Any suitable means may be provided for preventing overthrow 45 of the master wheel at the key strokes. The disconnection of the key from the computing mechanism, as aforesaid, conduces to the speed of manipulation of the machine. It also avoids liability of the type bar being 50 checked in its printing stroke by reason of the arrest of the computing devices at the completion of their strokes; since the type bar can continue in action after the key lever 3 has been disconnected from the computing 55 devices.

Said master wheel 29, as soon as it has completed the rotation of the computing wheel, and before the down stroke of a numeral key 2 is completed, moves or starts 60 to move to position to engage the live computing wheel, that is, the computing wheel 30 of the next lower denomination to the one that has just been operated. This jumping of the master wheel is initiated by said 65 trip 19, the latter having a second nose 40 to

engage a lug or crook 41 formed on the end of an arm 42 fixed upon a rock shaft 43. There are one crook 41 and one arm 42 for each trip; and therefore the devices 41, 42 and 43 may be taken together as constitut- 70

ing a universal device. The nose 40 is formed upon an ear 44 which is folded from the upper portion of the trip 19 and extends alongside of the nose 21. This nose 40 operates the part 41 of the universal device as 75 the trip disconnects itself from the pin 22; so that it is insured that the master wheel 29 shall not jump before its rotation is completed. The positions of the parts, when the nose 40 is depressing the member 41 of 80 the universal device, is seen at Fig. 9.

When said universal device is depressed in the manner indicated, a pendant arm 45 fixed upon the rock shaft 43 is swung forwardly, and, by means of a link 46, swings 85 an upstanding arm 47 on a rock shaft 48 at the rear of the machine. This rock shaft is journaled in any suitable supports 49, 50, and upon its inner end carries a releasing arm 51. This arm is depressed when the 90 shaft 48 rocks in the manner just stated; and during such depression, the arm 51 engages and carries down a pawl 52, which is normally in engagement with a tooth 53 of a wheel 54, which is fixed upon the shaft 55 95 which carries the pinion 11 and escapement wheel 12 of the carriage feeding mechanism. The wheels 54 and 12 are rigidly connected; while the pinion 11 has a ratchet connection 56 to the wheel 12, to permit the carriage to 100 run back to begin a new line while the wheels 12 and 54 remain stationary. The depression of the pawl 52 carries it down out of engagement with the tooth 53, as at Fig. 13; and as soon as said pawl escapes from 105 the tooth 53, a draw spring 57 snaps the pawl toward the right at Fig. 15 to engage it with the next tooth of the wheel 54, which at this time is stationary. Said pawl 52 is connected to the master wheel 29 to jump 110 the latter toward the right at Fig. 4 to position to engage the next lower computing wheel 30. This connection includes an arm 58, to which the pawl 52 is pivoted at 59; said arm fixed at its lower end to a horizontal rock shaft 60, which may be suitably journaled in the framework, and at its forward end carries an arm 61 having a slot-and-pin connection at 62 with a lever 63 of the first order, which is fulcrumed at 64 and 115 has at its upper end a pivotal connection 65 to a link 66. This link 66 extends toward the master wheel 29, and at its inner end is pivoted to a collar 67 which is confined in a groove 68 in the hub 69 of the master wheel; 120 said link 66 having a fork 70 to loosely bestride the shaft 28 to restrain the inner end of the link against vertical displacement. The hub 69 is splined at 67a to the master-wheel shaft or ratchet wheel shaft. The 125 65

spring 57 therefore, as soon as the pawl 52 is released from tooth 53, operates to engage said pawl with the next notch in the wheel 54, and simultaneously jump the master wheel 29 out of engagement with the dead computing wheel and into engagement with the live computing wheel; all of this occurs during the down stroke of the key 2, or at about the completion of said down stroke.

10 It will be seen that the pawl 52 is not only moved toward the right, but is also caused (preferably by the same spring 57) to jump up into the succeeding notch. A stop 71 prevents overthrow of the pawl 52, Fig. 15, and the master wheel 29 connected thereto.

15 At the time that the nose 40 of the double trip engages the universal member 41, the cam 39 is still in engagement with the tripping bar 35; and the cam action continues, so that the nose 40 is caused to release the universal member 41 at the final portion of the stroke of the key 2, so that the arm 51 may release the pawl 52 and permit the spring 57 to snap the pawl into the next 20 notch of wheel 54; the return movement of 25 51 and 45 being produced by a spring 72, Figs. 3 and 15.

During the last portion of the down stroke of the key 2, the heel 15 on the type bar 30 strikes the universal bar 16 and moves the carriage feeding dog 18 out of mesh with the escapement wheel 12 and the dog 14 into mesh therewith; no motion of the paper carriage taking place at this time. At the beginning of the return stroke of the key 2, 35 the dogs 13, 14 resume the initial positions at Fig. 3, and the escapement wheel 12 is permitted to turn one tooth, and the carriage 8 to advance one letter space. During this motion of the wheel 12, the wheel 54 drives the pawl 52 to the left from Fig. 15 position to the normal Fig. 7 position; and in consequence the master wheel 29 accompanies the live computing wheel 30 as the latter travels 40 to the left at Fig. 4 with the paper carriage 45 to the left at Fig. 4 with the paper carriage as the latter feeds a letter space.

If another numeral key is started down during the return of the operated key to normal position, it will be seen that the master wheel 29 will rotate, and will turn the computing wheel 30, during the travel of the carriage; since all the wheels, including the master wheel, are traveling together. It often happens that a second key is depressed 50 before the paper carriage completes its letter feeding movement; and sometimes the key is half way down before the carriage has made one half of a letter space movement. Owing to the provision of having the master wheel 29 travel with the carriage, in the manner stated, no harm results from such premature operation of the second numeral key, because the computing operation will proceed in a proper manner, and the paper carriage will be in position to receive the 55 60 65

impression by the time that the key is fully depressed. It will be seen that the necessity for relying wholly upon interlocking devices for preventing the carriage from traveling while a computing wheel is turning, and for preventing a computing wheel from turning while the carriage is traveling, is avoided. As each numeral key 2 returns, a spring 73, Fig. 3, snaps the trip 19 back over the pin 22; said spring connecting 75 the stem of the trip 19 directly to the key. The trips may be guided in a comb 74.

At Fig. 1 is shown a yielding arm 75 on the rock shaft 43, said arm having a locking tooth 76 to engage a tooth or notch of the master wheel 29 (Fig. 9) to lock the same temporarily at the completion of its rotation by any figure key 2, so as to prevent overthrow. This lock is promptly withdrawn, as the arm 75 returns to normal position simultaneously with the rock shaft 43, under the influence of spring 72, as soon as nose 40 of the double trip is released from the universal member 41 during the down stroke of the key 2. Said arm 75 has a hub, 80 whereby it is loosely mounted on the rock shaft 43; and a spring finger 77 projects from said shaft, and is caught at its other end by clips 78 on the arm 75. This spring permits slight additional motion of the rock 85 shaft 43 after the engagement of the locking pin 76 with the master wheel 29. Any other suitable means may be provided for locking the computing wheels against overthrow.

When the carriage is fed by any of the letter keys 1, the wheel 54 forces the pawl 52 toward the left at Fig. 16, together with the arm 58; the rock shaft 60 and the master wheel 29 also partaking of this idle movement. A cam 80 on the pawl is at this time 100 intercepted by a releasing pin 81, which is fixed upon the machine frame, and causes said pawl to escape from the wheel 54 at about the time the latter has made one half 105 of its step-by-step movement or from the dotted line to the full line position at Fig. 16. Upon such escape the spring 57 returns the pawl to the right at Fig. 16, and the cycle of movements is repeated for each 110 depression of any alphabet key 1.

The pawl 52 may be carried to the left at Fig. 16, and held out of the path of the wheel 54, by swinging down a finger-piece 82 pivoted at 83 upon the front portion of the framework and having an arm 84 which 115 engages a dependent arm 85 fixed upon the rock shaft 60. The key is swung to the Fig. 17 position, and thereby withdraws the pawl 52 entirely from the wheel 54; and arm 84 mechanically locks the parts in the Fig. 120 17 position; since said arm at this time extends at a right angle to the arm 85, the pressure of the latter being directly toward the pivot 83.

At the same time, the numeral keys 2 may 125 130

- be disconnected from the computing wheels, by the following means. A bail or rod or releasing bar 86 extends down from the shaft 35, which may be mounted to rock to 5 carry said bar 86 rearwardly to swing all of the trips 19 back far enough to clear the lugs 22 and 41, so that the numeral keys may be operated without disturbing the computing devices. An arm 87 is fixed upon 10 said rock shaft to be engaged by a pin or arm 88 secured to the arm 85, so that when the latter is moved to the Fig. 17 position, the trips 19 are also swung back and silenced.
- 15 The key 2*, Fig. 4, which is used for writing a character "0," is not provided with an arm 23, but its trip 19* has a nose 40 to engage a finger 41 carried by the rock shaft 43, so that although the master wheel 29 is 20 not rotated, still it is jumped to the next lower computing wheel when a "0" is written, so that the master wheel is in position to turn the next computing wheel in advance of the completion of the ensuing feeding 25 movement of the carriage.
- Variations may be resorted to within the scope of the invention, and portions of the improvements may be used without others.
- Having thus described my invention, I 30 claim:
1. The combination of numeral keys, a carriage, a master wheel, a gang of computing wheels, one of said master wheel and gang elements being connected to said carriage, means to enable the numeral keys to drive the master wheel, means for automatically effecting connection between the master wheel and the computing wheel of next lower denomination, during the down stroke 35 of each numeral key and after the wheel at the master wheel has been turned by said keys, and independently of the letter feeding movement of the carriage, and means for causing the master wheel and computing 40 wheels to travel together during the ensuing letter-feeding movement of the carriage.
  2. The combination with a letter feeding carriage and numeral keys, of a master wheel, a computing head, said master wheel 45 and computing head constituting companion elements one of which is connected up to the carriage to travel therewith, means for jumping the master wheel automatically to the live computing wheel as soon as it has turned 50 the preceding computing wheel, and means for causing the master wheel and computing head to travel together with the carriage during the ensuing letter feeding movement of the latter.
  3. The combination with a letter feeding carriage and numeral keys, of a master wheel rotatable during the early part of each key stroke, means effective after such rotation and before or during the completion 55 of the key stroke, for jumping the master wheel to the next computing wheel in the system, and means to return the master wheel during the next ensuing letter feeding movement of the carriage.
  4. The combination with a letter feeding carriage and numeral keys, of a master wheel rotatable by the numeral keys during the early part of each key stroke, means effective after such rotation and before or during the completion of the key stroke, for 60 jumping the master wheel to the next computing wheel in the system, and trip devices between said numeral keys and said master wheel to disconnect the master wheel from the control of the keys during the down stroke of the keys and after the complete turning of the master wheel.
  5. The combination with a computing mechanism, and a master wheel, of numeral keys for controlling the drive of the computing mechanism by the master wheel on the down stroke of said keys, and means for enabling the master wheel to jump from the dead computing wheel to the live computing wheel during, or at the completion of, the 65 down stroke of a key, to thereby increase the period of engagement of said master wheel with the live computing wheel.
  6. The combination with a letter-feeding carriage, a computing mechanism, and a master wheel, of means to enable said master wheel to move in one direction with the carriage throughout the letter feeding movement of the latter and to move in the opposite direction independently of the carriage.
  7. The combination with a series of computing wheels and a master wheel, of numeral keys for driving said master wheel, means for disconnecting a numeral key from the master wheel during the down stroke of the key, a spring controlled from said keys to cause the master wheel to jump to the live computing wheel, as soon as said master wheel is disconnected from the driving key, and means for restoring the master wheel to 100 normal position against the tension of said spring.
  8. The combination with a master wheel and a series of computing wheels driven therefrom, of a series of numeral keys, a series of spiral arms controlled by said keys, said arms controlling the drive of said master wheel, and operating trip connections between said arms and said numeral keys.
  9. The combination of a series of numeral keys, a master wheel, operating trip connections between the numeral keys and the master wheel, and master-wheel-jumping mechanism also having trip connection to said keys, both the operating trip connections and the jumping mechanism trip connection being released on the down stroke of the keys, the release of the said operating trip connections being followed immediately by that of the jumping mechanism trip connection,

whereby the master wheel may be jumped independently of the return of the keys to normal positions.

10. In a computing machine, the combination with computing mechanism, a master wheel therefor, and keys for driving said master wheel, of trip means to disconnect said keys and master wheel on the down-stroke of any key and after said key has driven said master wheel, and overthrow-preventing means for said master wheel operated by said trip means.

11. The combination with a master wheel and a series of numeral keys for driving the same on the down stroke of a key, of means for jumping the master wheel from one computing wheel to the next lower wheel at the last part of the down stroke of a key, and means for disconnecting the master wheel from the control of the key during the said down stroke of the key preparatory to the jumping movement of said master wheel.

12. The combination with a series of numeral keys, a master wheel and computing wheels, of connections pivoted to the keys and having hooks, pins over which said hooks catch, arms carrying said pins, a rock shaft from which said arms project, a driving pawl between said rock shaft and said master wheel, and means dependent upon the key strokes for disconnecting said hooks.

13. The combination with a series of numeral keys, a master wheel and computing wheels, of connections pivoted to the keys and having hooks, pins over which said hooks catch, arms carrying said pins from a rock shaft from which said arms project, a driving pawl between said rock shaft and said master wheel, means dependent upon the key strokes for disconnecting said hooks, cams or tappets on said hooks, a trip bar in the paths of said cams or tappets and a spring for returning said rock shaft in advance of the return of the key.

14. The combination with a carriage, a set of computing wheels, a master wheel and numeral keys, of a universal device operable by any numeral key, a wheel or rack connected to said carriage, a pawl normally in engagement with said wheel or rack and disengageable by said universal device, and a spring to advance the master wheel to the next lower computing wheel when said pawl is released, said pawl connected to said master wheel and moved by said spring into engagement with the next tooth on said carriage wheel, and caused by the carriage during the ensuing feeding movement thereof, to move the master wheel axially in unison with the feeding movement of the carriage, whereby said master wheel may be rotated by the next operated numeral key before said carriage and master wheel come to rest.

15. In a combined typewriting and computing machine, the combination with com-

puting wheels, a master wheel therefor, a traveling carriage, and numeral keys, of a universal device to prevent overthrow of said master wheel and operable by any numeral key, a controlling wheel, a pawl normally engaging said wheel and disengageable therefrom by said universal device, and means to advance the master wheel to the next lower computing wheel when said pawl is released, said pawl connected to said master wheel and moved by said advancing means into engagement with the next tooth on said controlling wheel, and caused by the carriage during the ensuing feeding movement thereof, to control the master wheel axially to hold it in engagement with the live computing wheel, whereby said master wheel may be rotated by the next operated key before said carriage comes to rest.

16. In a combined typewriting and computing machine, the combination with computing wheels, a master wheel therefor, a traveling carriage, and alphabet and numeral keys, of a controlling wheel, a pawl normally in engagement with said wheel and disengageable therefrom by any numeral key, and a spring to advance the master wheel to the next lower computing wheel when said pawl is released, said pawl connected to said master wheel and moved by said spring into engagement with the next tooth on said controlling wheel, said carriage causing said wheel to restore said spring to normal tension during the ensuing feeding movement of said carriage, to control the master wheel axially to hold it in engagement with the live computing wheel, whereby said master wheel may be rotated by the next operated numeral key before said carriage comes to rest, said spring being further tensioned to move said pawl to abnormal position during each operation of an alphabet key.

17. In a combined typewriting and computing machine, the combination with computing wheels, a master wheel therefor, a traveling carriage, and alphabet and numeral keys, of a controlling wheel, a pawl normally in engagement with said wheel, means controlled from any key for disengaging said pawl from said controlling wheel, a spring to advance the master wheel to the next lower computing wheel when said pawl is released, said pawl connected to said master wheel and moved by said spring into engagement with the next tooth on said controlling wheel, said carriage causing said wheel to restore said spring to normal tension during the ensuing feeding movement of said carriage, to control the master wheel axially to hold it in engagement with the live computing wheel, whereby said master wheel may be rotated by the next operated numeral key before said carriage comes to rest.

rest, said spring being further tensioned to move said pawl to abnormal position during each operation of an alphabet key, and a device to move and lock said pawl in said 5 abnormal position.

18. In a computing machine, the combination with computing wheels, of a master wheel, numeral keys to drive said master wheel, means for disconnecting said keys 10 from said master wheel, means to reciprocate said master wheel, an overthrow lock for said master wheel, and a universal member controlling said reciprocating means and said lock, said member operated by each key 15 immediately after said key is disconnected from the master wheel.

19. The combination with numeral keys, a master wheel controlled on the down stroke thereof, and computation wheels operable by said master wheel, of means effective upon the down strokes of the keys subsequent to the rotation of the master wheel, for effecting relative jumping movement 20 between the master wheel and computation 25 wheels for engaging the master wheel with the live computation wheel.

20. The combination with numeral keys, a master wheel controlled on the down stroke thereof, and computation wheels operable by said master wheel, of a step-by-step feeding carriage for controlling certain movements of said master wheel, and means effective upon the down strokes of the keys 30 subsequent to the rotation of the master 35 wheel for effecting relative jumping between the master wheel and computation wheels for engaging the master wheel with the live computation wheel, said jumping movement being distinct from and anticipative 40 of the movement of said carriage.

21. The combination with numeral keys, a master wheel connected with said keys to be controlled thereby, and computation wheels operable by said master wheel, of 45 means effective upon the down strokes of the keys subsequent to the rotation of the master wheel for effecting relative jumping movement between the master and computation wheels for engaging the master wheel 50 with the live computation wheel, and means for disconnecting the active key from the master wheel preparatory to the jumping or anticipative movement of the latter.

22. The combination with numeral keys, 55 a master wheel connected with said keys to be controlled thereby, and computation wheels operable by said master wheel, of a step-by-step feeding carriage for effecting relative denominational movements between 60 said master wheel and said computation wheels, means effective upon the down strokes of the keys subsequent to the rotation of the master wheel, for effecting relative jumping movement between the master 65 wheel and computation wheels for engaging

the master wheel with the live computation wheel, said jumping movement being distinct from and anticipative of the movement of said carriage, and means for disconnecting the active key from the master wheel 70 preparatory to the jumping or anticipative movement of the latter.

23. The combination of numeral keys, a master wheel or member, means controllable by the keys for causing the master wheel to 75 rotate variably during the down strokes of the keys, computation wheels or members operable by said master wheel, and means effective upon the down strokes of the keys subsequent to the rotation of the master 80 wheel, for effecting relative jumping movement between the master wheel and computation wheels for engaging the master wheel with the live computation wheel.

24. The combination with numeral keys, a master wheel connected to said keys to be controlled thereby, and computing wheels operable by said master wheel, of a single member connected to each key, and means rendered effective by said member on the 90 down-stroke of said key subsequent to the rotation of the master wheel for disconnecting said key from said master wheel, for effecting relative jumping movement between said master wheel and the computing 95 wheels to engage the master wheel with the live computing wheel, and for reconnecting each key to the master wheel upon the return stroke of the key.

25. The combination with a series of computing wheels, of a master wheel for driving said computing wheels *seriatim*, and means for vibrating said master wheel back and forth axially between drives thereby of each computing wheel. 100

26. The combination with a series of computing wheels, of a master wheel for driving said computing wheels, actuating mechanism for said master wheel, a series of numeral keys controlling the action of said actuating 110 mechanism, locking mechanism normally disconnected from the keys for preventing overthrow of said master wheel, and means enabling each key as it controls said actuating mechanism, to disengage itself therefrom and then engage and operate said locking mechanism to prevent overthrow of said master wheel after the drive thereof by said actuating mechanism has ceased. 115

27. The combination with a series of computing wheels, of a master wheel for driving said computing wheels, actuating mechanism for said master wheel, a series of numeral keys controlling the action of said actuating mechanism, locking mechanism for preventing 120 overthrow of said master wheel, and means enabling each key, after controlling the action of said actuating mechanism, to disengage itself therefrom and then momentarily operate said locking mechanism 125 130

to prevent overthrow of said master wheel and subsequently escape from said locking mechanism to enable said locking mechanism to free itself from said master wheel.

- 5 28. The combination with a series of computing wheels, of a master wheel for driving said computing wheels *seriatim*, a traveling carriage, said computing wheels being mounted to travel with said carriage, an
 10 escapement mechanism for said carriage, an escapement mechanism for said master wheel, a series of numeral keys for controlling the drive of said master wheel and the escapement mechanism of said carriage, means for actuating the escapement mechanism of said master wheel on the driving stroke of a key and before actuation of the escapement mechanism of said carriage, to enable the engagement of the master wheel
 15 with the next lower computing wheel before the carriage is released for a step-by-step movement, and means to cause said master wheel and said computing wheels to travel together with said carriage during the step-
 20 by-step movement thereof.

29. The combination with two primary elements, to wit, a series of computing wheels and a master wheel, of a carriage traveling and controlling during its travel-
 30 ing movement, a relative movement between said primary elements, so that said master wheel may drive said computing wheels *seriatim*, means for anticipating a relative movement between said primary elements by a movement of one of said primary elements, to bring said master wheel into register with the next computing wheel, and means for returning said last-mentioned primary element with the ensuing step
 35 movement of said carriage, so as to maintain said master wheel in register with the computing wheel with which it is anticipatively in engagement, during the movement of said carriage.

40 45. 30. The combination with two primary elements, to wit, a series of computing wheels and a master wheel for driving said computing wheels *seriatim*, of a carriage for controlling said primary elements, one
 50 of said primary elements traveling continuously with the carriage, means enabling the second of said primary elements to travel to anticipate the traveling movement of the first of said elements, and means for moving
 55 both said primary elements together when the first of said elements moves with said carriage.

31. The combination with a series of computing wheels, of a master wheel for
 60 rotating said computing wheels *seriatim*, said master wheel and said computing wheels having a relative traveling movement to enable said master wheel to register *seriatim* with said computing wheels, a
 65 series of numeral keys for controlling the

rotation of said master wheel, and means acting during the down stroke of each numeral key, to bring about said relative traveling movement between said master wheel and said computing wheels, so as to cause
 70 a change in registration during the down stroke of each numeral key, of the master wheel from one computing wheel to the next succeeding computing wheel.

32. The combination with a series of computing wheels, of a master wheel for driving said computing wheels, a carriage traveling to effect a relative movement between said computing wheels and said master wheel, said computing wheels traveling with
 80 said carriage, and means for effecting a double feed of said master wheel so as to move while said computing wheels are stationary, and also so as to move with said computing wheels when said computing
 85 wheels travel with said carriage.

33. In a combined typewriting and computing machine, the combination with a carriage, of printing mechanism, a series of computing wheels, a master wheel for en-
 90 gaging said computing wheels *seriatim* to drive the same, a series of numeral keys for controlling the action of said master wheel, said carriage and said printing mechanism; operating trip connections from said nu-
 95 meral keys for turning said master wheel, means for locking said master wheel when said turning movement by said numeral keys is completed, means for jumping said master wheel from the computing wheel it
 100 has just turned to the live computing wheel, and a connection operable by said keys common to said locking means and said jumping means.

34. In a combined typewriting and computing machine, the combination with a carriage, of a series of computing wheels, a master wheel for driving said computing wheels *seriatim*, a series of numeral keys for controlling the movement of said carriage and the rotation of said computing wheels, means for driving said master wheel from said numeral keys, means for locking said master wheel as its rotation by a key is completed, and means for jumping said
 110 master wheel to the live computing wheel as it completes the turning of a computing wheel, and means connected to each key for actuating said driving means and subsequently said locking and jumping means.

35. In a combined typewriting and computing machine, the combination with a series of computing wheels, of a master wheel engaging and driving said computing wheels *seriatim*, a series of numeral keys
 115 for driving said master wheel, a member for each numeral key, connections from said members to drive said master wheel, a trip carried by each member, means operated thereby for locking said master wheel after
 120 125 130

it has been turned by any one of said numeral keys, and means for disconnecting each member as actuated by the corresponding numeral key, so as to interrupt the connection between the numeral key and the master wheel.

36. In a combined typewriting and computing machine, a series of computing wheels, a master wheel for driving said computing wheels *seriatim*, a series of numeral keys for controlling said master wheel, a member for each of said numeral keys, forming part of a connection between the numeral keys and the master wheel, a trip carried by each member, means controlled thereby for jumping the master wheel to the next computing wheel, and means also operated by said trips for positively locking said master wheel against rotation just before it is jumped from one computing wheel to the next computing wheel.

37. The combination with a series of computing wheels, of a master wheel for driving said computing wheels *seriatim*, driving mechanism for driving said master wheel, a series of numeral keys for controlling the extent of drive of said master wheel by said driving mechanism, a series of individual connections to said numeral keys, each of such connections arranged to operate said driving mechanism and disengaging itself therefrom during a down stroke of the numeral keys, locking mechanism for said master wheel, jumping mechanism for said master wheel, and tripping devices operated by said individual connections for actuating said jumping mechanism to bring the master wheel into register with the next computing wheel and concomitantly actuate said locking mechanism to prevent the rotation of the master wheel while jumping from one computing wheel to the next computing wheel.

45. 38. A computing typewriter combining numeral keys, a master wheel, a totalizer comprising denominational digit wheels, a carriage providing relative traverse between master wheel and totalizer, means to enable the numeral keys to effect a feeding movement of the carriage, means to enable the numeral keys to control the drive of the master wheel, and means for automatically effecting connection between the master wheel and the digit wheel of next lower denomination during the downstroke of each numeral key after the digit wheel at the master wheel has been turned by said key, said last-named means acting independently of the feeding movement of said carriage.

39. A combined typewriting and computing machine having computing mechanism including denominational members, a master member, and a step-by-step feeding carriage; and comprising, in combination,

means for jumping the master member to the denominational member of lower order prior to the carriage movement and in a direction opposite thereto, and means to move the master member and computing mechanism with the carriage and in the same direction during a substantial part of the step-by-step feeding movement of the carriage.

40. A combined typewriting and computing machine, having computing mechanism comprising denominational members, a master member therefor, a step-by-step letter-feeding carriage, an escapement mechanism therefor, said computing mechanism being movable in the same direction as the letter-feeding movement of said carriage; and comprising, in combination, means for jumping the master member to the denominational member of lower order, prior to the carriage movement, and in a direction opposite thereto, and means acting through the medium of said escapement mechanism for moving said master member and carriage in the same direction during the letter-feeding movement of said carriage, to thereby maintain said master member in engagement with said denominational member of lower order during said movement.

41. A combined typewriting and computing machine, having computing mechanism, comprising denominational members, a master member therefor, a step-by-step letter-feeding carriage, an escapement mechanism therefor, including an escapement shaft, said computing mechanism being movable in the same direction as the letter-feeding movement of said carriage and comprising, in combination, means for jumping the master member to the denominational member of lower order prior to the carriage movement, and in a direction opposite to such movement, comprising a pawl connected to the master member, and a spring for acting on said pawl, and means comprising a ratchet on said escapement shaft for positively engaging said pawl during the normal turning of said shaft to feed said carriage in letter-space direction, for moving said master member in the same direction as the carriage movement during the letter-feeding movement thereof, to thereby maintain said master member in engagement with said lower computing member during said movement.

42. A combined typewriting and computing machine, having computing mechanism, comprising denominational members, a master member therefor, a step-by-step letter-feeding carriage, an escapement mechanism therefor, said computing mechanism being movable in the same direction as the letter-feeding movement of said carriage; and comprising, in combination, means for jumping the master member to the denominational member of lower order prior to the carriage movement, and in a direction opposite to such movement, comprising a pawl connected to the master member, and a spring for acting on said pawl, and means comprising a ratchet on said escapement shaft for positively engaging said pawl during the normal turning of said shaft to feed said carriage in letter-space direction, for moving said master member in the same direction as the carriage movement during the letter-feeding movement thereof, to thereby maintain said master member in engagement with said lower computing member during said movement.

national member of lower order prior to the carriage movement and in a direction opposite thereto, comprising a pawl connected to the master member, and a spring for acting on said pawl and means for putting said spring under tension through the medium of said escapement mechanism on the letter-feeding movement of said carriage, said spring being released from tension subsequent to the completion of the stepping movement of the carriage.

43. In a computing machine, the combination with computing mechanism, a master wheel therefor, and keys for driving said master wheel, of a member universal to said keys, connections between said keys and said member, said member having arms projecting in different radial directions for engagement by said connections, whereby said keys may differentially drive said master wheel, and means for disengaging each of said connections from its corresponding radial arm at the same point in the down-stroke of each numeral key.

44. In a computing machine, the combination with computing mechanism, a master wheel therefor, and keys for differentially driving said master wheel, of means to disconnect said keys and master wheel at the same point in the down-stroke of each key, and means common to all of said keys and operated immediately after any key has reached said point of disconnection to prevent overthrow of said master wheel.

45. In a computing machine, the combination with computing mechanism, a master wheel therefor, and keys for driving said master wheel, of a member universal to said keys, connections between said keys and said member, said member adapted to be engaged and differentially driven by said connections, means to disconnect said keys and master wheel at the same point in the down-stroke of each key, and means for preventing overthrow of said master wheel when driven by any key, said overthrow-preventing means including a member having a series of arms projecting in the same direction, each adapted to be engaged by each key connection immediately after said connections have reached said point of disconnection from said universal member.

46. In a computing machine, the combination with computing mechanism, a master wheel therefor, and keys for driving said master wheel, of a member universal to said keys, connections between said keys and said member, said member having arms projecting in different radial directions for engagement by said connections, whereby said keys may differentially drive said master wheel, means for disengaging each of said connections from its corresponding radial arm at the same point in the down-stroke of each numeral key, and means for preventing over-

throw of said master wheel when driven by any key, said means including a member having a series of arms projecting in the same direction, each adapted to be engaged by each key connection immediately after said connections have reached said point of disconnection from said universal member. 70

47. In a combined typewriting and computing machine, the combination with computing mechanism, a letter-feeding carriage, and numeral keys controlling said carriage, of a master wheel driven by said keys, and means controlled by each numeral key on its down-stroke for preventing overthrow of the master wheel driven thereby, and causing 80 the master wheel to automatically jump to the live computing wheel in anticipation of the feeding movement of the carriage.

48. In a combined typewriting and computing machine, the combination with computing mechanism, a letter-feeding carriage, and numeral keys controlling said carriage, of a master wheel driven by said keys, and a member universal to all of said keys to prevent overthrow of said master wheel 90 when driven by any key, and to cause said master wheel to jump to the live computing wheel in anticipation of the feeding movement of the carriage.

49. In a combined typewriting and computing machine, the combination with computing mechanism, a letter-feeding carriage, and numeral keys controlling said carriage, of a master wheel driven by said keys, and a universal member actuated by any of said 100 keys on their down-strokes to cause said master wheel to jump to the live computing wheel in anticipation of the feeding movement of the carriage.

50. In a combined typewriting and computing machine, the combination with computing mechanism, a letter-feeding carriage, and numeral keys controlling said carriage, of a master wheel driven by said keys, a universal member for operating said master 105 wheel, and a universal member controlling the jumping of said master wheel to the live computing wheel in anticipation of the computing movement of said wheel, both said universal members being controlled by said 110 numeral keys.

51. In a combined typewriting and computing machine, the combination with computing mechanism, a letter-feeding carriage, and numeral keys controlling said carriage, of a master wheel driven by said keys, a universal member controlling the operation of said master wheel by said numeral keys, and a universal member for preventing overthrow of said master wheel after being 115 driven by each key, said numeral keys acting on said universal members successively.

52. In a combined typewriting and computing machine, the combination with computing mechanism, a letter-feeding carriage, 120

and numeral keys controlling said carriage, of a master wheel driven by said keys, a universal member to operate said master wheel, a second universal member, and means controlled thereby to prevent overthrow of said master wheel driven by any key and also to control the jumping of said master wheel to the live computing wheel in anticipation of the carriage feeding movement, said keys 10 operating on said universal members successively.

53. In a combined typewriting and computing machine, the combination with computing mechanism, a master wheel therefor, a letter-feeding carriage, and keys for differentially driving said master wheel and controlling said carriage, of means to disconnect each of said keys from said master wheel at the same point in the down-stroke 20 of each key, and means controlled by said keys immediately after reaching said point to cause said master wheel to jump to the live computing wheel in anticipation of the feeding movement of the carriage.

54. In a combined typewriting and computing machine, the combination with computing mechanism, of a master wheel therefor, a letter-feeding carriage, keys, connections from said keys for differentially driving said master wheel, said connections including a member universal to said keys, said member having arms projecting in different radial directions for engagement by said connections whereby said keys may differentially drive said master wheel; means for disengaging each of said connections from its corresponding radial arm at the same point in the down-stroke of each numeral key, and means for causing said master wheel to jump to the live computing wheel in anticipation of the feeding movement of the carriage immediately after said

key has reached said point of disconnection, said means comprising a member having a series of arms projecting in the same radial 45 direction, each arm adapted to be engaged by each key connection after said connections have reached said point of disconnection from said universal member.

55. In a combined typewriting and computing machine, the combination with computing mechanism, a master wheel therefor, a letter-feeding carriage, and numeral keys controlling said carriage and master wheel, of connections between the numeral digit 55 keys and said master wheel for controlling the latter, and connections from said digit keys and the zero key for controlling the jumping of the master wheel to the live computing wheel in anticipation of the feeding 60 movement of said carriage.

56. In a combined typewriting and computing machine, the combination with computing mechanism, a master wheel therefor, a carriage, and numeral keys controlling said carriage and master wheel, of means for jumping the master wheel automatically to the live computing wheel as soon as it has turned a computing wheel, connections from said numeral keys to said jumping means, and from said numeral keys to said master wheel, said connections including a plurality 70 of members, all of said members connected to said digit keys having a trip for operating said master wheel, and a trip for operating said master-wheel jumping means, the member connected to the zero key having a trip for the master-wheel jumping means only.
